UNITED STATES PATENT OFFICE

171,693

ADJUSTABLE LEG

Ralph J. Fisher, Pasadena, Calif.

Application August 3, 1953, Serial No. 26,248

Term of patent 14 years

(Cl. D33—1)

To all whom it may concern:

Be it known that I, Ralph J. Fisher, a citizen of the United States and resident of Pasadena, county of Los Angeles, State of California, have invented a new, original, and ornamental Design for an Adjustable Leg, of which the following is a specification, reference being had to the accompanying drawing forming a part hereof.

The single figure is a perspective view of an adjustable leg showing my new design.

I claim:

The ornamental design for an adjustable leg, substantially as shown.

RALPH J. FISHER.
